UNITED STATES PATENT OFFICE.

WILLIAM E. FOWLER, JR., OF MOUNT LEBANON, PENNSYLVANIA.

CAR TRUCK.

Application filed February 18, 1925. Serial No. 10,218.

The invention described herein relates to certain improvements in side frames or parts of a car truck supported by the axle boxes and in turn forming supports for the ends 5 of the bolsters. The invention has for its object a truss-shaped side frame having its compression and tension members formed of wrought metal and integral one with the other at their ends, and the strut forming 10 the bolster columns formed of cast metal.

The invention is hereinafter more fully described and claimed.

In the accompanying drawings forming a part of this specification, Fig. 1 shows the 15 improved frame in side elevation and having ends secured to the axle boxes; Fig. 2 is a top plan view showing a preferred construction of the top of an axle box for the attachment of the ends of the truss; Fig. 3 is 20 a sectional elevation on a plane indicated by the line III—III, Fig. 2; Fig. 4 is a sectional elevation on a plane indicated by the line IV—IV, Fig. 1; Fig. 5 shows a side and 25 end elevation of a blank from which the compression and tension members of the truss shown in Fig. 1 are formed; Fig. 6 is a view similar to Fig. 1 illustrating a preferred construction of truss-shaped side 30 frame; Fig. 7 is a sectional view on a plane indicated by the line VII—VII, Fig. 6; and Figs. 8 and 9 illustrate successive steps in 35 the formation of the truss.

In the practice of the invention a rolled bar preferably H-shaped in cross section, the 40 flanges and web being preferably of uniform thickness as shown in Fig. 5, is so cut or slotted for a suitable distance along its median line as to form legs *a* and *b*. The cutting or slotting does not extend the entire 45 length of the bar, as it is desired that the end portions of the legs should be integral one with the other. When forming the truss from an H-shaped section, it is preferred to remove the web portion *c* for the desired distance along the bar.

After the bar is slotted as described, it is suitably heated and by suitable mechanism, one of the legs as *a*, is upset longitudinally to reduce its length and cause a bowing out 50 of the other leg. The extent of upsetting will of course be dependent upon the desired depth of the truss.

The strut of the truss is next placed in position, said strut being formed by a box-like casting into which ends of the bolster and the spring plank of the truck project.

The sides of the casting form the columns 1 for guiding the bolster in its vertical movements and also prevent any lateral movement thereof, and are connected by the 60 top and bottom portions 2 and 3 of the casting, and hence each column will be reinforced as against lateral strains by the other column. The bottom member of the casting forms the support for the spring plank 65 of the truck.

The outer faces of the upper and lower portions of the casting are provided with spaced ribs or checks 5 and 6 forming lateral 70 bearings for the compression and tension members 7 and 8 of the truss. Suitable means are employed to prevent movement of the box or strut longitudinally of the truss, as for example, in the construction shown in Fig. 1, the upper portion of the box is riveted to the compression member and suitable stops 8^a are secured to the tension member on opposite sides of the casting.

The depth of the truss, i. e., the greatest distance between the tension and compression members is made somewhat less than the depth of the strut or column casting so the compression and tension members must be sprung apart a sufficient distance not only to permit of the casting being placed in position, but also to ensure that the strut will be placed under compression and be tightly gripped between said members.

While the integral ends of the truss may be secured to the axle box 9 in any suitable manner, the construction shown in Figs. 1 to 4 has been found suitable. In order to prevent the box from moving laterally of the truss, ribs or checks 10 are formed on the top of the box, said ribs being spaced 90 such distances apart that the ends of the truss can be seated between them, and between these ribs 10, a transverse rib 11 is formed, said rib being adapted to extend into a seat 12 formed in the underside of 95 the ends of the truss resting on the box. In the order to hold the box from any turning movement relative to the truss, the side of the box is provided with a bracket 13, which is adapted to be secured to the tension member of the truss. In the construction shown, the bracket is provided with a seat 14 in which the tension member is held by caps 15 riveted to the brackets. The boxes 100 are secured to the ends of the truss by rivets 16^a which preferably pass through the webs 105 and also the ribs 11 on the boxes.

110

In the construction shown in Fig. 1, the attachment of the strut or column casting and its maintenance in position lengthwise of the truss, is effected by rivets, which are subjected, when a truck embodying the improvements claimed herein is in use, to a shear action. In order to effectively resist such shearing action, the rivets should be relatively large or a multiplicity of smaller rivets employed. In the construction shown in Figs. 6, 7, and 8, provision is made for avoiding the use of rivets where they would be subjected to shearing action.

In forming the truss member, a bar preferably H-shaped in cross section is so cut or slotted on its median line that the legs *a* and *b* formed by cutting or slotting, are integrally connected not only at their ends, but also at a plurality of points intermediate their ends, as indicated at *d*, *e* and *f*. By means of a saw or other mechanism, two of the connecting sections, as *d* and *f*, are severed, as indicated at *x*, from the leg *b* which in the completed truss will form the tension member, and the intermediate section *e* is severed from the leg *a*, as indicated at *y*. The leg *a* is next upset thereby bowing the leg *b*. The strut is formed by two box-like sections, the sides 1 of which, when the sections are placed in position, form the columns employed for laterally supporting and guiding the bolster. At their upper and lower ends, the box sections are provided with ribs 16 and 17 adapted to bear against the edges of the compression and tension members, 7 and 8, and each of the sections are so notched in line with the vertical sides and as indicated at 18, for the reception of the inwardly projecting lugs *d* and *f* on the compression member, as shown in Figs. 6 and 7. The upper ends of the box sections are also provided with fingers 19 adapted to project over the compression member and tie the latter to the strut.

The lower longitudinal members of the box sections are also notched as indicated at 20 to form a socket when the sections are placed in position for the reception of the lug *e* on the tension member. The box sections are placed in position from opposite sides of the truss, the tension and compression members being sprung apart for that purpose, and are held in such position by rivets 18 passing through flanges 21 on the column portions of the section. The frame forming the strut may be made of steel or malleable cast-iron, as best suited to meet the shocks and strains to which the frame would be subjected in use.

In a truck embodying the improvements described and claimed herein, the load-carrying bolster is supported by the tension member the ends of which rest upon and are secured to the axle boxes. The load on the tension member tends to deform such mem-

ber and draw the axle boxes and wheels towards each other. Such action is prevented by the compression member, which has its ends connected to the end of the tension member and to the axle boxes. In the practice of the invention, it is preferred that the positions of the tension member on opposite sides of the column casting or strut should be at such an angle to the correspondingly located portion of the compression member and the ends of the truss be so secured to the axle boxes, that the lines of stress of the tension and compression members will intersect in a vertical plane coinciding with the axes of the axles as shown in Figs. 1 and 6 and will therefore so neutralize each other that there will not be any turning movement at the end of the truss.

It will be observed that in the construction shown in Fig. 6 the strut or frame is held from lateral movement relative to the truss by the bearing of integral portions of the former on integral portions of the truss, and that the latter is tied to the box by fingers integral with the latter.

I claim herein as my invention:

1. A side frame for trucks consisting of tension and compression members formed of wrought metal and having their ends integrally connected and a cast metal frame interposed between the tension and compression members and forming the columns and spring plank support of a truck in combination with axle boxes provided with means engaging the united ends of the tension and compression members transversely and longitudinally, and means for tying the boxes to the tension member.

2. A side frame for trucks having in combination tension and compression members, each provided with an inwardly projecting lug, a strut consisting of a frame formed of complementary sections, each section being provided with means for engaging the lugs on the tension and compression members, and means for holding such sections in engagement with the lugs.

3. A side frame for trucks having in combination therewith tension and compression members, a strut consisting of a frame adapted to form bolster columns and spring plank support of a truck, and means integral with the compression member adapted to so engage the strut as to prevent movement of the strut laterally and longitudinally of the compression member.

4. A side frame for trucks having in combination tension and compression members, the compression member being provided with inwardly projecting lugs and the tension member with an inwardly projecting lug intermediate horizontally of the lugs on the compression member, a strut consisting of a frame adapted to form the bolster col-

umn and a spring plank support of a truck, and provided with sockets for the reception of the lugs on the compression and tension members.

5 5. A side frame for trucks having in combination tension and compression members, the compression member being provided with inwardly projecting lugs and the tension member provided with an inwardly projecting lug intermediate horizontally of the lugs on the compression member, a strut consisting of a frame adapted to form the bolster column and a spring plank support of a truck and provided with sockets for the 10 reception of the lugs on the compression and tension members, and fingers on the strut

adapted to overlap the compression member.

6. A car truck having in combination a pair of side frames which comprise a bar of substantially H-shape slotted transversely of its web portion and expanded to constitute 20 tension and compression members joined integrally at their respective ends, a strut consisting of a frame adapted to form the bolster columns and spring plank support 25 disposed between and engaged by said tension and compression members and axle boxes secured to the ends of said frame for journaling a plurality of wheel axles.

In testimony whereof, I have hereunto set 30 my hand.

WILLIAM E. FOWLER, JR.
